UNITED STATES PATENT OFFICE.

STEPHEN A. HUNTLEY, OF ELK POINT, SOUTH DAKOTA,

FIREARM.

SPECIFICATION forming part of Letters Patent No. 654,895, dated July 31, 1900.

Application filed May 6, 1899. Serial No. 715,850. (No model.)

To all whom it may concern:

Be it known that I, STEPHEN A. HUNTLEY, a citizen of the United States, residing at Elk Point, in the county of Union and State of South Dakota, have invented a new and useful Improvement in Firearms, of which the following is a specification.

My invention relates particularly to an improvement in automatic repeating shotguns, though the invention is not limited to this particular class of firearms.

My primary object is to provide arms of this description with quick-acting power-operated mechanism for automatically reloading the gun from a suitable magazine after each discharge.

A further object is to improve the general construction of the various operative parts of the mechanism of the gun.

My invention consists in the improved power-operated mechanism, the improved details of construction of the gun mechanism generally, and in various combinations of parts, all as hereinafter fully set forth and claimed.

In the accompanying drawings, which illustrate my invention as embodied in an improved automatic repeating shotgun, Figure 1 is a broken view, in right side elevation, of the improved gun; Fig. 2, a broken central vertical longitudinal section through the gun. Fig. 3 is an enlarged section similar to Fig. 2, and showing the breech-block in its forward position; Fig. 4, a section similar to Fig. 3, but showing the breech-block in its retracted position; Fig. 5, a horizontal section on line 5 of Fig. 3; Fig. 6, a horizontal section on line 6 of Fig. 3; Fig. 7, a horizontal section on line 7 of Fig. 4; Fig. 8, a right side and a front end view of the breech-block; Fig. 9, a bottom plan view of the breech-block; Fig. 10, a vertical section on line 10 of Fig. 9; Fig. 11, a rear upper perspective view of the carrier-operating bell-crank; Fig. 12, a front upper perspective view of the shell or cartridge carrier or transerrer; Fig. 13, an enlarged right side view of power mechanism which automatically operates the mechanism for reloading the gun; Fig. 14, a section of the same on line 14 of Fig. 15; Fig. 15, a bottom view of the same; Fig. 16, a horizontal section on line 16 of Fig. 13; Fig. 17,

a transverse section on line 17 of Fig. 3; Fig. 18, a broken section similar to Fig. 3 with many parts omitted and showing details of the means employed for actuating the power-mechanism escapement; and Fig. 19 a front broken view of the detachable trigger-plate.

It may be stated preliminarily that the breech-block serves in its rearward movement to extract the discharged shell and bring it within the action of an ejector, also preferably operated by the breech-block, by which the shell is thrown out through a lateral opening in the breech-frame. In its rearward movement the breech-block also at the proper moment engages the bell-crank, which actuates the shell or cartridge carrier or transerrer, causing the latter to be elevated to a proper position to bring a new charge into line with the gun-barrel. Before the breech-block can be withdrawn, however, the bolt which secures it in its closed position is necessarily first unlocked, and preferably at almost the same instant the firing-pin is locked. In its rearward movement the breech-block preferably further serves to retract the hammer and set the mainspring. In its forward movement the breech-block first forces the newly-elevated shell partially into the gun-barrel, and during its further forward movement depresses the carrier and completes the insertion of the new charge into the barrel. When the breech-block reaches the front end of its traverse, a spring-actuated bolt serves to lock it in its closed position, and preferably said bolt serves when entering its socket to unlock the firing-pin. During its downward movement the carrier serves, by means of a suitable spring-held piece with which it is provided, to depress the spring-held shell-stop at the rear end of the magazine to permit the magazine-spring acting on a piston-like shell-follower to force a new shell into the carrier. A stationary shell-stop at the rear end of the carrier limits the rearward movement of the shell entering the carrier. It thus appears that by a reciprocating movement the breech-block serves in an improved manner to extract and eject the used shell, cock the gun, reload the gun, and recharge the carrier with a shell to be used in the next reloading. The breech-block is itself preferably reciprocated by means of the stored-power mechanism.

shown, joined by a connecting-rod to an extension of the breech-block. The power mechanism is controlled by an escapement which preferably is actuated by an auxiliary trigger when it is desired to open the works to charge the magazine. At the time of charging the magazine a loaded shell may also be introduced into the shell-chamber of the gun-barrel. Thereafter the recoil of the gun is utilized for actuating the escapement. The means shown for reciprocating the connecting-rod is an epicycloidal gear driven by the stored power of a spring, as hereinafter fully described. The pinion to which the connecting-rod is joined in making the circuit of the gear within which it moves carries the rear end of the connecting-rod rearwardly and forwardly along one certain diameter of the larger or fixed gear. The spring-power causes this movement to occur once at each discharge of the gun, when the pawl which locks the gear-train is for an instant withdrawn from engagement by the recoil of the gun.

A represents the gun-stock; B, the breech-frame; C, the gun-barrel; D, the fixed ammunition-magazine; E, the breech-stock; F, the spring-power motor; G, the rod connecting the motor and breech-block; H, the shell-carrier; I the carrier-operating bell-crank; J, the hammer; K, the firing-pin; L, the main or discharge trigger, and M the auxiliary or power-escapement trigger. The breech-block moves in a horizontal plane, being guided in its movement by flanged guide-grooves a , Fig. 17, at the top of the breech-block chamber and grooves a' , Fig. 3, in the side walls of said chamber. The breech-block, Fig. 8, is provided on its upper side at its front end with a head b , supplied with flanges b' , which engage the grooves a , and at its rear end with laterally-projecting lugs b^2 , which engage the grooves a' . The block is provided with a downwardly-inclined rear extension E', comprising two parallel arms c c' , connected by a cross-piece c^2 . Perforated lugs c^3 serve for the attachment of the connecting-rod G. The lugs are joined by a pin d , Figs. 3 and 5, which engages a slot d' in the end of the rod G, which projects between the lugs, thus forming a lost-motion connection. Said rod is provided with an offset head or projection d^2 , Fig. 5, carrying a pin d^3 , so located as to engage the rear end of a lever N, which serves to move the breech-block bolt preparatory to the movement of the breech-block. The firing-pin K passes through the breech-block, Fig. 4, and is held normally retracted by a spring. When in its retracted position, except when the breech-block is in its closed position, the pin is secured against accidental movement by a spring-held lock-piece e, Fig. 10, provided with a lug e' , which engages a notch on the lower surface of the pin. The piece e is pivoted to the breech-block at e^2 , is actuated by a spring e^3 , and is provided with an upturned rear end e^4 , which projects into a recess e^5 , which receives the front end of

the breech-block bolt. A screw e^6 , projecting into a slot e^7 in the firing-pin, serves to limit the rearward movement of the latter. The vertical head b of the breech-block is slotted at its upper surface to receive a spring extractor-catch f, pivoted at f' in a manner to permit it to slide over the shell-flange and engage the latter to effect a withdrawal of the shell at the next retraction of the breech-block.

P is the breech-block-locking bolt, Fig. 3, preferably flat and pivotally secured to the frame at g and normally bearing down upon the upper surface of the breech-block under the action of a spring g'. The figure shows the manner in which the front end of the bolt, under the action of its spring, is forced into the recess e^5 at the rear end of the breech-block, thereby firmly locking the block in its closed position and at the same time pressing down upon the rear end of the firing-pin lock-piece and unlocking the firing-pin. Fig. 3 shows the relative positions of the parts after the firing-pin has been unlocked by said bolt and driven forward by the hammer in discharging the weapon.

Figs. 3 and 4 best illustrate the means for raising the breech-block-locking bolt to unlock the breech-block. The lever N, mentioned in connection with the connecting-rod pin d^3 , is pivotally connected to the frame at h. At its front end it is provided with a bifurcated head which engages a lug h' on the lower end of a slide h^2 , which moves in a vertical slot h^3 on the internal surface of the left wall of the breech-block chamber. The upper end of this slide is pivotally joined to the front end of the locking-bolt P, sufficient play being allowed at the guide-slot to permit of the desired movement. It will appear from an inspection of Fig. 3 that the pin d on the connecting-rod G is in position to engage the rear upwardly-inclined end of the lever N in the first rearward movement of the connecting-rod and unlock the breech-block, after which the front end of the slot d' of the rod engages the pin d of the breech-block and retracts the latter.

The breech-block is provided on its under surface with a recess k, affording at its front and rear ends, respectively, shoulders k' and k^2 , which engage the short arm k^3 of the carrier-actuating bell-crank and tilt the latter to elevate or depress the carrier, as the case may be. The carrier, Fig. 12, is provided on its sides with integrally-formed vertical guide-lugs l l' , the former of which projects a certain distance above the carrier-body and affords a stop, limiting the rise of the carrier. These lugs move in vertical guide-slots l^3 , Figs. 5 to 7. The rear end of the carrier-body is provided with a slot m, within which moves a rib m' on the lower side of the breech-block at the time when the carrier is in its extreme elevated position and the breech-block is moving forward. This rib projects slightly beyond the forward end of the breech-block

to afford a support for the flange of a shell. The end is beveled at the lower side, as shown in Fig. 8, to engage a corresponding bevel m^2 , Fig. 3, of the carrier, and thus slightly de-
5 press the carrier after the front end of the breech-block has partially traversed the surface of the carrier in closing the breech.

The bell-crank I is provided with two long arms $n\ n'$, the ends n^2 of which are provided 10 with curved upper and lower edges. The arms embrace the rear portion of the carrier and project into slots n^3 in the lugs $l\ l'$, which are provided with curved upper and lower surfaces which coact with the curved ends 15 of the arms $n\ n'$. The bell-crank is pivoted in the breech-frame at n^4 , and it will readily be understood that when the front end of the slot k of the breech-block engages the arm k^3 of the bell-crank the latter is tilted rear- 20 wardly, thereby elevating the carrier, and when the rear end of the slot k engages the arm k^3 the bell-crank is tilted forwardly, thereby lowering the carrier. In Figs. 3 and 25 4 the arm k^3 is shown dotted to indicate its position; but it will be understood that said arm really belongs to the removed section of the bell-crank.

Fig. 12 shows the carrier provided at its left front corner with a rearwardly-movable 30 spring-held lug p , whose forward movement is limited by a pin p' . This lug is provided with a beveled front surface p^2 , and the function of the lug is to engage an inner beveled surface p^3 (Figs. 3 and 6) of a spring-held 35 magazine shell-stop p^4 , working in a horizontal slot in the left vertical wall of the breech-block frame and provided with an inturned end p^5 , affording a shoulder for engaging the rear end of the rearmost shell 40 in the magazine. When the carrier rises, the beveled surface p^2 of the spring-held lug is engaged by the rear vertical surface of the inturned end p^5 of the shell-stop, causing the lug to slip past the shell-stop and to resume 45 its former position for again actuating the stop at the next downward movement of the carrier to permit the recharging of the latter. The magazine is provided with a shell-follower D' and a magazine-spring D², which 50 is confined between the frontend of the magazine and the follower. A stationary shell-stop Q' serves to limit the movement of the shells Q as they are expelled singly from the magazine.

55 R represents the trigger-plate, which is preferably formed separately from the remainder of the breech-frame and has mounted upon it the hammer, mainspring, and triggers, all removable with the trigger-plate and without removal of the breech-block. In Fig. 19 the plate is shown provided with lateral flanges q, which move in longitudinal grooves q' in the side walls of the breech-block chamber, as indicated in 60 dotted lines in Fig. 4. This permits withdrawal of the trigger-plate from the rear after the stock and the screw-fastenings of the

plate are removed. One of these screw-fastenings is indicated by the letter q² and one by the letter q³. The gun-stock is shown 70 attached to the trigger-plate by a screw r and to a rearward extension r' at the upper side of the breech-frame by screws r².

Referring to Figs. 3, 4, and 6, the hammer J is shown pivoted on a pin s between lugs s' 75 on the upper side of the trigger-plate. On each side of the hammer, slightly back of its pivotal point, is a stirrup s², pivoted on a pin s³ and provided with laterally-projecting pins s⁴. The pins s⁴ engage the ends of a 80 two-prong mainspring S, secured to the trigger-plate by a screw s⁵. The hammer J, which moves in the, virtually, slotted extension E' of the breech-block, in striking the firing-pin, is provided on its under side (in 85 its cocked position) with a recess s⁶, provided at its rear portion with an offset for engaging a rearward projection s⁷ at the upper end of the trigger L. The trigger-spring s⁸, secured to the trigger-plate by a screw s⁹, holds 90 the trigger in engagement with the hammer when the latter is drawn back. A sliding safety lock-piece s¹⁰, provided on its upper surface with two depressions adapted to be engaged by the rear end of a spring s¹¹, serves 95 to securely lock the trigger against discharge when shoved back beneath a shoulder s¹² on the front edge of the upper portion of the trigger. In the rear of the trigger L is located the trigger M, which, as stated, is used 100 for actuating the power-mechanism escape- 105 ment by hand when desired. The trigger M is pivoted on the trigger-plate screw q² and at its upper end is pivotally connected by a screw s¹³ to the front end of a rod T, which 110 connects, Fig. 18, with the automatic device for working the escapement of the spring- 115 driven mechanism above mentioned.

To permit shells to be ejected from the breech-block chamber, the right wall of the 110 latter is provided with an opening V, guarded by a slide V', moving in a groove V², Figs. 1 and 5, the slide being secured by a screw s¹⁴ to the front end of the breech-block and moving therewith. As already indicated, the 115 extractor-catch f and shell-rest m' at the front end of the breech-block serve to withdraw the used shell from the shell-chamber of the gun-barrel. In Figs. 4 and 7 is shown the means for ejecting the shell from the breech-block chamber. A horizontal ejector-lever t, sheathed normally in a slot t' in the left wall of the breech-block frame, is pivoted near its rear end on a vertical pin t². The outer surface of the short arm of the lever is depressed, 120 and upon it bears the front end of a spring t³, which serves normally to keep the lever sheathed in the slot t'. The lever t is itself provided at its pivotal point with a horizontal slot t⁴, in which is pivoted on the pin t² a lug t⁵, which stands normally at right angles to the lever t. A spring t⁶ serves normally to hold 125 the lug at right angles to the lever, and any effort to force the lug rearwardly beyond a

right angle causes it to engage a shoulder afforded by the rear end of the slot t^4 and move the front end of the lever t or the ejector-arm inwardly. Thus the lug t^5 forms with the long end of the lever t a bell-crank. The lug is capable of rotating forwardly to be sheathed in the slot t^4 . The breech-block is provided on its left side with a slot t^7 , whose front end affords a shoulder t^8 . In the forward movement of the breech-block the lug t^5 is engaged by the shoulder t^8 and slips past the latter, allowing the lug to enter the slot t^7 . In the rearward movement of the block the lug is again engaged by said shoulder, and this time acts to rock the long end of the lever t inwardly to the position shown in dotted lines in Fig. 7. This action occurs just before the front end of the shell clears the shell-chamber, and the bell-crank, acting quickly, strikes the rear portion of the shell a blow which throws it with much force, rear end foremost, from the breech-block chamber. At this instant the opening V of the breech-block frame is of course unclosed.

It may be here mentioned that the upper interior surface of the frame B is provided with a central longitudinal slot v for the extractor-catch f to move in, and the rear end of the shell-chamber of the barrel C is provided with recesses $v' v^2$ for the parts f and m' to enter when the gun is closed; also, to permit insertion of the breech-block into its guide-grooves a cross-recess v^3 is provided, Fig. 3, at the rear end of the slots a , Fig. 17, for the head b of the breech-block to enter.

The spring-driven power device for actuating the breech-block is clearly shown in Figs. 13 to 16, inclusive. It comprises a left side plate F' , in which is journaled one end of a spring-driven shaft F^2 , on which is fixedly secured a gear F^3 , which meshes with a journaled pinion F^4 , which in turn meshes with a two-part gear F^5 , posts F^6 , supporting a right side plate F' , a spring F^8 , fixed at one end to a post and at its opposite end to the shaft F^2 , a fixed internally-toothed gear F^9 , resting on and secured by means of screws w to a semicircular ring or lug w' , which is secured by the same screws to the plate F' , and an escapement-pawl F^{10} , pivotally secured on a pin w^2 to a slotted lug w^3 , projecting from the front end of the fixed gear F^9 and under the action of its spring w^4 normally holding the gears against movement. The inner part x of the two-part gear F^5 is keyed to the adjacent end of a stud x' , journaled at the center of the fixed gear F^9 and provided at its opposite end with a rigid arm x^2 , which projects outward to the inner edge of the teeth on said fixed gear, where it is recessed at one side, as indicated by the dotted line x^3 in Fig. 13, to receive the inturned rear end x^4 of the pawl F^{10} . The inner part of the gear F^5 is provided with a spring held pin x^5 , having its end beveled in one direction to adapt it to enter beveled recesses x^6 on the interior surface of the outer portion of the gear F^5 . It will thus

be seen that in winding up the spring F^8 , which is done by applying a key to the angular end of the shaft F^2 , the outer part of the gear F^5 slips readily upon its center, the latter being held fixed through the medium of the arm x^2 and the pawl F^{10} . The arm x^2 is provided on its outer surface with a stud x^7 , on which is journaled a pinion x^8 , of one-half the diameter of the gear F^9 and meshing therewith. The pinion x^8 is provided at one of its teeth with a stud x^9 , with which the rear end of the connecting-rod G is pivotally joined. In the rotation of the gear x^8 within the gear F^9 the stud x^9 describes a straight line, as is well understood. In Fig. 1 the gun-stock is shown provided with a removable plate Y to allow the power mechanism to be inserted. The stock may be formed in any suitable manner, however.

Figs. 2, 6, and 18 particularly show the means by which the escapement is worked to permit the power mechanism to actuate the breech-block after each discharge. A spring-held weight W is provided with a square longitudinal perforation, which receives a fixed angular guide-rod W' . The recoil of the gun serves through the inertia of this weight to compress the spring, and the recoil of the latter forces the weight against the front end of the pawl F^{10} and disengages its inturned end x^4 from the arm x^2 , permitting the latter to make one revolution, when it is again engaged by the pawl, the resilience of whose spring causes it quickly to recover from the shock of the blow given by the weight W . The weight-spring in its passive condition performs the function of holding the weight normally against displacement when the gun is inverted or given any abrupt movement in handling, thus preventing accidental actuation of the escapement, and in its active condition after compression by the recoil of the gun it also performs the function of operating the weight to actuate the escapement. It is hardly necessary to add that when the weapon is discharged the frame and other fixed parts are moved backwardly by the recoil so quickly as to compress the weight-spring before the inertia of the weight can be overcome and that the resilience of the spring furnishes a positive and certain means for operating the weight, and while this seems to be the best possible construction, yet the invention is not to be limited thereto. The term "spring-held" as applied to the escapement-actuating weight in the appended claims is not to be understood as implying that the weight is non-yielding, but the contrary, for while one purpose of the spring is to hold or retain said weight against accidental movement, yet a further purpose is to accomplish this and still leave the weight yielding to permit it to be separated from the escapement-pawl in order to acquire sufficient momentum in its return movement to actuate the pawl. A moment after the discharge the weight yields to the action of the spring under the increase of re-

silence acquired during the violent movement of recoil. Any suitable resilient body may be employed for causing the rearward movement of the weight. Preferably a spring 5 is employed for the twofold purpose stated.

To actuate the power-escapement by hand when desired, the trigger M is provided. The rod T, connected therewith, is provided with what may be termed a "spear-head" having 10 the inclined surfaces y^1 y^2 and the lateral lugs y^3 . The weight W is provided on its under side with a recess, affording a shoulder y^4 . The spear-head moves in a slotted guide y^5 , having guide-surfaces y^6 y^7 y^8 for engaging, respectively, the surface y^9 , lugs y^3 , and surface y^2 . The rod T is held normally in the position shown in Fig. 18 by springs y^9 y^{10} . When the trigger M is pressed, the spear-head moves upwardly, pressed by the spring 20 y^{10} , and engages the shoulder y^4 of the weight, drawing the weight forward. The lugs y^3 guide the spear-head till the surface y^2 engages the surface y^8 , when the head is depressed, releasing the weight.

25 Fig. 5 shows a spring-held stop z, beveled at its front side, which may be shoved in to engage the left lug b^2 of the breech-block to lock the gun in its open position while the magazine is being recharged. In the rearward movement of the breech-block the stop is carried over said lug b^2 and engages the front side thereof. The stop z may be located at any suitable point to engage and lock the power mechanism. Preferably it is 30 so located as to allow a slight forward movement of the breech-block before stopping it, as clearly shown in Fig. 7.

The functions of the various parts have been explained and a brief connected description of the operation of the gun will be 40 added.

The manner of assembling the parts will be readily understood by the mechanic from the description thus far given. The power-spring F⁸ is wound by means of a key applied at a keyhole X. As explained, one end of the spring F⁸ is fixed to a stationary post, and the other end acts on the gear-train, the locking connection being at the two-part 45 gear F⁵, the central part of which is while the winding occurs a fixed part. To charge the magazine, the trigger M is pressed to cause the escapement to work and permit the power mechanism to open the gun. At this 50 time the button z is pressed in to engage the breech-block and hold the parts in their open position. At this time the carrier is elevated, and the shells are inserted one at a time from the lower side of the breech-frame 55 through the opening occupied by the carrier when in its depressed position. After the magazine is charged and before releasing the breech-block from the stop z a shell is inserted through the lateral opening in the 60 breech-frame, the carrier being depressed the necessary distance by hand. This is permitted by a release of the pressure on the

bell-crank I by the slight forward movement of the breech-block mentioned. When the pressure on the stop z is released, the stop 70 disengages itself from the breech-block and the latter moves forward, depressing the carrier to its lowest position. In this movement the magazine-shell stop is actuated and the carrier charged. When the breech-block 75 reaches its closed position, the locking-bolt P is forced downward into the recess e⁵ and unlocks the firing-pin. In the previous rearward movement of the breech-block it will be recalled the hammer was forced down by 80 the under surface of the block into engagement with the trigger. The gun is therefore now ready for discharging, and at the recoil of each discharge the escapement is actuated 85 to free for an instant the power mechanism to permit it to cause one reciprocation of the breech-block.

It is believed that many of the operative parts used in combination with the reciprocating breech-block are of novel construction. The feature of a recoil-actuated device controlling the escapement of the stored-power mechanism is of great importance, as is also the feature of combining therewith means whereby said device may be manipulated by hand.

The epicycloidal gear used for actuating the breech-block, while peculiarly effective for the purpose, may be replaced by any suitable mechanism so far as other features of the invention are concerned.

Many changes in details of construction and the substitution and omission of certain parts may be made without departure from my invention. Hence I wish to be understood as intending no limitation by the particular description given above, except as shall appear from the appended claims. The mechanism is claimed wherever applicable in firearms using fixed ammunition.

The term "recoil-actuated means" where used in the appended claims is intended to apply to any construction wherein the principle of producing a relative movement between certain parts of the mechanism by the recoil of the piece is relied on in the actuation of the escapement. It is not regarded as indispensable that said means be separated from the escapement.

What I claim as new, and desire to secure by Letters Patent, is—

1. In a firearm, the combination with frame, barrel, magazine, extracting and ejecting means, and a reciprocable breech-block, of stored-power mechanism connected with and actuating said breech-block, an escapement for said power mechanism, and recoil-actuated means for controlling said escapement, substantially as and for the purpose set forth.

2. In a firearm, the combination with frame, barrel, magazine, extracting and ejecting means, a reciprocable breech-block, stored-power mechanism connected with and actuating said breech-block, and an escapement for

said power mechanism, of an escapement-actuating weight movably mounted in said frame and with relation to which the frame is moved by the recoil in firing, substantially as and for the purpose set forth.

3. In a firearm, the combination with frame, barrel, magazine, extracting and ejecting means, a reciprocable breech-block, stored-power mechanism connected with and actuating said breech-block, and an escapement for said power mechanism, of a spring-operated escapement-actuating weight movably mounted in said frame and contacting with said escapement, with relation to which weight the frame is moved by the recoil in firing, substantially as and for the purpose set forth.

4. In a firearm, the combination with frame, barrel, magazine, extracting and ejecting means, a reciprocable breech-block, stored-power mechanism connected with and actuating said breech-block, and an escapement for said power mechanism, of a spring-operated escapement-actuating weight movably mounted in said frame, and hand-operated means for moving said weight and compressing its spring to give it the necessary resilience for moving the escapement in the operation of introducing the initial cartridge into the barrel, substantially as and for the purpose set forth.

5. In a firearm, the combination with frame, barrel, magazine, and reciprocable breech-block, of means for actuating said breech-block, comprising a connecting-rod, gear mechanism connected with said rod for reciprocating it, a spring for actuating said gear mechanism, a spring-held pawl controlling the movement of the gear mechanism, and a yielding spring-held weight contacting with said pawl, substantially as and for the purpose set forth.

6. In a firearm, the combination with frame, barrel, magazine, and reciprocable breech-block, of means for actuating said breech-block, comprising a connecting-rod, an epicycloidal gear connected with said rod, a gear-train for actuating said epicycloidal gear, a spring for driving said train attached at one end to a stationary part and at the opposite end to the train, a spring-held pawl in the course of said gear-train permitting ready movement of the parts in one direction for winding purposes, and transmitting power in the opposite direction, an escapement-pawl controlling the movement of the epicycloidal gear, and means for actuating said escapement, substantially as and for the purpose set forth.

7. In a firearm, the combination with frame, barrel, magazine, and reciprocable breech-block, of means for actuating said breech-block, comprising a connecting-rod, an epicycloidal gear connected with said rod, a coil-spring for actuating said gear, an escapement for the gear, and a yielding spring-held device operating under the resilience of its spring to actuate the escapement when withdrawn from

the escapement and then released, substantially as and for the purpose set forth.

8. In a firearm, the combination with frame, barrel, magazine, ejector, carrier, and a reciprocable breech-block, of means for reciprocating said block, comprising a casing, fixed gear F^9 , stud x^1 provided with arm x^2 carrying gear x^8 , connecting-rod G , two-part gear F^5 provided between its parts with a spring-held catch, pinion F^4 , gear F^3 , spring F^8 , and an escapement for the power mechanism thus described, substantially as and for the purpose set forth.

9. In a firearm, the combination with frame, barrel, magazine, ejector, carrier, hammer, main trigger, and reciprocable breech-block, of stored-power mechanism, an escapement therefor, an auxiliary trigger, a yielding spring-held weight contacting with said escapement said weight being provided with a recess, a rod connected at its front end with said auxiliary trigger and provided at its rear end with means for engaging said recess, and means for guiding the rear end of the rod and releasing it from said weight, substantially as and for the purpose set forth.

10. In a firearm, the combination with frame, barrel, magazine, carrier, and reciprocating breech-block, provided with a rear slotted extension, a firing-pin extending to the slotted extension, a connecting-rod joined to said extension, spring-actuated power mechanism connected with said rod a hammer beneath said breech-block in the rear of its forward position and working when released in the slot of said extension to engage said pin, a mainspring for the hammer, and a trigger, substantially as and for the purpose set forth.

11. In a firearm, the combination with barrel, frame, and reciprocable breech-block provided at its rear end with a recess affording a locking-bolt socket, of a spring-held locking-bolt for said block pivoted to said frame in the rear of the block, a firing-pin in said block provided with a recess, and a spring-held lock-piece carried by the breech-block and entering said recess, said lock-piece being provided with an extension projecting into said socket, substantially as and for the purpose set forth.

12. In a firearm, the combination with barrel, frame, and reciprocable breech-block provided at its rear end with a recess affording a locking-bolt socket, of a spring-held locking-bolt for said block pivoted to said frame in the rear of the block, a vertical slide joined to said bolt, a lever pivotally joined to said frame and engaging said slide, and means connected with the breech-block for actuating said lever, to raise said bolt and for then actuating the breech-block, substantially as and for the purpose set forth.

13. In a firearm, the combination with frame, barrel, magazine, and reciprocable breech-block, of a vertically-movable carrier, and a bell-crank provided with two long arms

embracing the sides of the carrier and engaging bearings thereon and with a short arm projecting into the path of the breech-block, substantially as and for the purpose set forth.

5 14. In a firearm, the combination with frame, barrel, magazine, and reciprocable breech-block, of a carrier provided with lateral vertical lugs moving in slots in the frame, said lugs being provided with slots, and a bell-crank provided with arms embracing the sides of said carrier and entering said slots and with an arm projecting into the path of the breech-block, substantially as and for the purpose set forth.

15 15. In a firearm, the combination with barrel, breech-frame, and reciprocable breech-block provided with extractor means, and with shoulders for engaging a lug, of an ejector-arm, pivoted near its rear end in one side of the breech-frame on a vertical pivot and provided with a recess, a lug pivoted in said recess adjacent to the rear wall thereof, and a spring for holding said lug normally at right angles to said arm and against said rear wall, whereby the lug is engaged by the breech-block in the rearward movement thereof to actuate the ejector-arm and is sheathed by said block in its forward movement, substantially as and for the purpose set forth.

20 16. In a firearm, the combination with frame, barrel, magazine, spring-held-shell follower, vertically-movable carrier, reciprocable breech-block, and means for actuating the carrier, of a spring-held magazine-shell stop, and a spring-held actuating-lug for said

stop on said carrier, said stop and actuating-lug being provided with beveled surfaces for permitting them to ride upon each other, in the manner set forth and for the purpose 4c specified.

17. In a firearm, the combination with frame, barrel, magazine, and reciprocable breech-block, of means for actuating said breech-block, comprising a connecting-rod, 45 an epicycloidal gear connected with said rod, a coil-spring for actuating said gear, an escapement for the gear, and means for actuating said escapement, substantially as and for the purpose set forth.

18. In a firearm, the combination with barrel, breech-frame, and reciprocable breech-block provided toward its rear end with a recess affording a locking-bolt socket, of a spring-held locking-bolt for said breech-block 55 pivoted to said frame in the rear of the block, a lever N pivotally connected to the frame, connecting means between the front end of said lever and said locking-bolt, a rearward extension on the breech-block, a connecting-rod for reciprocating said breech-block, pin-and-slot connection between said breech-block extension and the front end of said connecting-rod, a stud on the front end of said connecting-rod engaging said lever N, and means 6c for actuating said connecting-rod, substantially as and for the purpose set forth.

STEPHEN A. HUNTLEY.

In presence of—

R. I. SPENCER,
D. W. LEE.
